WEB REGULATING MECHANISM

Michael J. Milmoe, Glen Ellyn, Ill., assignor to
 F. B. Redington Co., Chicago, Ill., a corporation
 of Illinois

Application June 9, 1933, Serial No. 675,037

16 Claims. (Cl. 271—2.6)

The present invention relates to feeding mechanism for webs such as are used in packaging machines and which are generally cut into strips of predetermined length to form wrappers for packages. Usually such webs have printed matter thereon for indicating the contents of the package or the like and means must be provided for cutting the web into strips at predetermined points along the web between the various sections 5 of printed matter so that the printed matter bears a certain relation to the article wrapped when the strip is cut and wrapped about the article.

Since it is very difficult to provide a feeding 15 means which will at all times feed the exact amount of web in timed relation to the rest of the wrapping mechanism and particularly the cut-off knives, and due to the stretching of the web, slippage, etc., it is necessary to provide some 20 means which cooperates to adjust the feed automatically so that at all times the proper feeding of the web will take place and the web will be cut at the desired points. In high speed wrapping machines, it is almost impossible to regulate 25 manually the position of the web and furthermore even if it were possible to adjust the same manually, it is extremely difficult for the operator to tell when an adjustment is necessary.

Accordingly the present invention has for its 30 object, the provision of means for adjusting the feed for the web in such a manner that the web is always cut at predetermined points with respect to the printed matter thereon within certain small limits. The limits can be changed as 35 desired.

The basic principle upon which my invention operates is the feeding of the web at a speed which varies from the actual desired feed for the web so as to insure a definite variation in one 40 direction from that desired. As the feed of the web continues, the total variation becomes greater. In other words, the variation causes an accumulation of errors which finally results in a total variation which should not be exceeded. 45 At this point, an adjusting means operated by the web itself comes into operation and corrects for the variation and the accumulation of errors again begins.

More specifically my invention contemplates 50 what is commonly known as an "electric eye" which is a light sensitive cell which responds to variations in light intensities which it receives, the variation of the intensity of light received by 55 the cell actuating a corrective device which in

the present instance is a variable drive which varies a definite amount on each actuation.

Another object of this invention resides in the provision of a drive to a web which drives the web at a greater rate of speed than would be theoretically desired or necessary. Therefore there is introduced into the web feed an error which accumulates which would soon cause an over feed which would position the printed matter improperly with respect to the cutting knives, 10 and the error would in time become so great that the web would be cut through the printed matter so that a part of the printed matter intended for one wrapper would appear on two wrappers. Therefore when the over feed becomes too great, 15 the driving mechanism for the web is changed preferably a definite amount to retard the feed temporarily and correct for the accumulated error. This correction is only introduced when the total error exceeds a certain amount so that if there is a slippage of the feeding mechanism with reference to the web which reduces the normal intended over feed for the web, the 20 correcting mechanism does not come into operation. Whenever the total error exceeds the 25 desired feed whether it be in one foot of travel of the web or 100 feet of travel of the web, the correcting mechanism becomes operative and introduces a lag in the feeding mechanism in such a manner that the total error is reduced within 30 the permitted limits of tolerance.

Another object of this invention is to provide means whereby variations in the feed of a web are automatically controlled by an electric eye or similar device.

Another object of this invention resides in providing a device which is operative on opaque materials as well as on transparent materials.

Another object of this invention is to provide means whereby delicate webs of material are fed along a predetermined path and any error in their feed compensated for without putting a strain on the material itself by holding it back positively against the feeding means which tends to pull the same forward.

Other objects of this invention will appear hereinafter as the description thereof proceeds, the novel features, arrangements and combinations being clearly set forth in the specification and claims appended hereto.

In the drawings:

Fig. 1 is a front elevation of a device embodying my invention with parts broken away for the sake of clearness;

Fig. 2 is a detail view of the pawl and ratchet 55

mechanism for introducing a correction into the drive to the web, the same being shown in rear elevation;

Fig. 3 is a view similar to Fig. 2 showing the parts in different positions of adjustment;

Fig. 4 is a plan view of the mechanism shown in Fig. 1;

Fig. 5 is a cross-section taken substantially along the line 5—5 of Fig. 1;

10 Figs. 6 and 7 show different positions for the web shown in Fig. 5;

Fig. 8 is a cross-section taken substantially along the line 8—8 of Fig. 1;

15 Fig. 9 is a section taken substantially along the line 9—9 of Fig. 1;

Fig. 10 is a plan view of the mechanism shown in Fig. 2;

Fig. 11 shows the schematic wiring diagram for operating the correcting mechanism; and

20 Fig. 12 is an enlarged plan view of the timer.

Referring now more particularly to Figs. 1 and 4, the reference character 20 illustrates the base of the machine and on this base there is supported a bracket 21 secured thereto. 22 indicates the 25 web which is to be fed and in the present instance is a piece of transparent material such as "cellophane". The reference character 23 indicates the single web of material as it leaves the roll 22 and this is fed over a roll 24 along guides indicated 30 generally at 25 past a casing 26 having a light sensitive cell 27 therein. The casing is provided with an opening 28 in the side of the casing adjacent the web 23. The web is fed downwardly to the feed rolls 29 which are geared together by 35 gears 30 secured to the same shafts as the rolls 29 so that the rolls 29 operate in unison with each other. The material fed between the rolls 29 passes between a pair of rollers 31 carrying the cut-off knives 32 which in the present instance 40 are such as to form a serrated edge on the strips 33 which are cut from the web by the knives 32. I have indicated the position at which light passes through the opening 28 to the cell 27 as position A and the position at which the web is cut as B. 45 See also Figs. 5, 6, and 7. The distance between these two positions A and B is fixed.

The webs illustrated in Figs. 5, 6, and 7 are provided respectively with the markings C, C¹, and C². Usually there is other printed matter on the 50 web and this is illustrated in the drawings by the letters XYZ, grouped together. It is desired to cut the web midway between adjacent groups of printed matter on the web, or at predetermined points with respect to these groups of letters or 55 other printed matter appearing on the web. In each of Figs. 5, 6, and 7 I have illustrated the webs at the positions which they occupy at a certain predetermined position of the parts of the feeding and cut-off mechanism. To make the illustration of my invention rather simple, I have indicated the position of the web at the instant the knives 32 cut the web and at the same instant at A there comes into operation, a certain correcting device presently to be described which will make a 60 correction in the web feed if the feed of the web varies more than a predetermined amount from the desired feed therefor. Actually in operation, the device at A does not come into operation at the same time that the web is cut at B. All that is 65 necessary is that the device at A operate in timed relation to the cut-off mechanism at B so that the adjustment will be with respect to the position at which the web is cut.

In Fig. 5, I have illustrated the position of the 70 web at its initial adjustment by the operator. In

this adjustment, the markings C arrive at a position just short of the position A so that they are not within the controlling beam of light which is projected through the film at the position A. In other words, the beam of light is not screened by 5 the marking adjacent the position C. As will appear hereinafter, whenever the light passes uninterruptedly through the transparent web, no correction is introduced in the web feed, but however in the event that a marking such as C¹ in 10 Fig. 6 arrives at the position A at the instant the correcting device becomes operative, the beam of light is cut off and as a result, the correction is introduced for the mechanism is such that the correction is introduced whenever the beam of 15 light is cut off. This actuates the correcting mechanism which retards the feed of the web so that successive markings are just short of the position A at the instant of operation of the correcting mechanism, such as is illustrated at C² in 20 Fig. 7. After the correction has been introduced, the rollers 29 which give an over feed to the web, feed the web with a slight over feed until the over feed again brings the markings at the position A at the time the correcting mechanism becomes 25 operative, at which time another correction is introduced.

I have stated that the correcting mechanism is such that it comes into operation when the beam of light is cut. However, a different type 30 of correcting means which operates on the reverse principle can be used. Thus the entire web can be dark so as to prevent the passage of the light normally through the web and the markings C, C¹, and C² can be transparent portions of the web. 35 The device can also operate on opaque materials and when such materials are used instead of having the light beam projected through the material, the light is reflected off the material. The mechanism for actuating the correcting mechanism is illustrated in Fig. 11 and in this figure, the web 23 is indicated in the same position with respect to the position A at the instant of operation as the web in Fig. 6 bears to the position A. The reference character 26 in this figure represents 40 the walls of the casing for the photo-electric cell 27. The beam of light projected through the web 23 is created by the source of light 34 and the condenser 35 which concentrates the rays of light on the photo-electric cell 27 through the web 23. If 45 a portion of these light rays are screened as by the markings C thereon, the amount of light falling on the photo-electric cell 27 is diminished and as a result a relay mechanism of any well known type such as indicated at 36 becomes operative to 50 actuate the correcting mechanism.

The relay 36 may be of the type illustrated in Patent No. 1,273,627, granted July 23, 1918, to Irving Langmuir and includes a reversing switch 55 for causing the same to operate when the photo-electric cell is shielded from the rays of light or when the rays are directed thereagainst as may be desired.

The photo-electric cell is connected to the relay by the leads 37. The power lines are indicated at 60 38 and lead into the relay 36. There also are leads 39 to the source of light 34. A separate timing circuit is connected to the relay and this circuit includes the leads 40, timer 41 oscillating in timed relation to the movements of the feeding 65 mechanism about the axis 42, and a solenoid 43 which is adapted to actuate the rod 44 in a vertical direction whenever the solenoid becomes operative. The relay is adapted to close the circuit within the relay by the ends of the leads 40 70 75

and the timer 41 also closes the remaining break in the circuit at the opposite ends of the leads 40. Fig. 11 illustrates the position of the parts at the instant of closing of the timer 41, the same being 5 inoperative at all other times, and therefore it is impossible except when the timer is in the position shown in Fig. 11 to operate the solenoid 43. However, one more condition must be present before the solenoid will become operative and that 10 condition is that the relay 36 must be closed to complete the circuit through the leads 40, timer 41 and solenoid 43. Normally, as already explained, the photo-electric cell will not operate the relay when it is receiving a sufficient amount 15 of light, but when the amount of light is diminished, the relay becomes operative. Therefore, if the marking C appears opposite the position A when the timer 41 is closed, the light to the photo-electric cell 27 is diminished and the relay becomes 20 operative. Since the timer 41 is also closed, the solenoid is operated and the rod 44 is moved vertically and actuates the means which introduces the correction into the feed.

If, however, the marking C does not appear at 25 the position A when the timer is closed, the result is that the relay remains open and the solenoid will not become operative.

The feed rolls and timer shaft 60 both derive 30 their movement from the same source of power as do also the knives 32 so that these parts are all operated in unison with each other. The source of light 34 is always operative to throw a beam of light toward the web. The main drive shaft is indicated at 45 and is connected by a 35 chain 46 to a jack shaft 47 to drive the same. A chain 48 trained over a sprocket on the shaft 45 and a similar sprocket on the shaft 50 shown in Fig. 8 is used to drive the rolls 31 which carry the knives 32. The shaft 50 has the axis thereof 40 co-incident with the axis of the roll 31 carrying the cut-off knife 32 shown at the right in Fig. 1. The roll 31 shown at the left is rotated by means of the gears 51 meshing with each other and mounted on the shafts which carry the rolls 31. See 45 particularly Fig. 4.

The roll 29 at the left in Fig. 1 is positively driven by the chain 52 from a sprocket secured to the rear end of the shaft which carries one of the rolls 29 as is best illustrated in Fig. 8. The 50 rolls as previously described have inter-meshing gears 30 which cause them to rotate in opposite directions to feed the web. The chain 52 is trained over a sprocket 53 on the shaft 54 which shaft also carries a gear 55 which meshes with the gear 56 on the shaft 47 driven by the chain 46 from the main drive shaft 45. The gear 55 is not directly connected to the shaft 54 but is normally connected thereto by a pawl and ratchet mechanism which later will be described. When 55 the position of the gear 55 with respect to the shaft 54 is altered by altering the adjustment of said pawl and ratchet mechanism, the drive to the feed rolls 29 will be changed to introduce the correction. The pawl and ratchet mechanism is so 60 arranged that when the pawl is disconnected from the ratchet, the gear 55 continues to be actuated but the shaft 54 lags and moves relatively to the gear 55. A corresponding lag occurs in the rolls 29, the feed being continued immediately when 65 the pawl again engages the ratchet. The main drive shaft is actuated in any suitable manner as by a belt trained over the pulley 57 secured rigidly to the shaft 45.

The shaft 47 carries a bevel gear 58 meshing 70 with a similar bevel gear 59 on a vertically ar-

ranged shaft 60 which shaft forms a part of the timing mechanism as is more clearly illustrated in Fig. 12. In this figure, it will be noted that the shaft 60 is provided on one side thereof with a flat spot 61. A fixed contact 62 and pivoted contact 41 are mounted on the boss 64 surrounding the shaft 60. A spring 65 normally urges the pivoted contact member 41 toward the contact member 62. Normally the shaft 60 holds the contacts out of engagement with each other but when the shaft 60 rotates to a position to bring the flat spot 61 thereof opposite the follower 66 on the contact 41, the contact 41 will move toward the contact 62 and close the gap therebetween 10 completing the electrical circuit through the relay 15 36 and leads 40 in the manner previously described. As previously brought out, the correcting mechanism cannot be operated unless the contact member 41 is in engagement with the contact member 62. The pawl and ratchet mechanism previously referred to to correct excessive over-feed of the web and the means for actuating said pawl and ratchet mechanism are best 20 illustrated in Figs. 1, 2, 3, 8, and 9.

In Figs. 8 and 9, it will be noted that the gear 25 55 is secured to a sleeve 63 and the sleeve 63 also has a disk 67 secured thereto. Pivoted to the disk 67 are a pair of pawls 68 and 30 69 which are normally urged against the ratchet 70 secured to the shaft 54 by means of the springs 71 and 72 respectively. It will be noted that normally the pawl 68 operatively engages the face of a tooth on the ratchet but the pawl 69 does not, the same being spaced somewhat from the operative face of an adjacent tooth but in a position to engage the tooth if the pawl 68 is raised. The normal drive to the rolls 29 is therefore through the intermediacy of the gears 56 and 55, sleeve 63, disk 67, pawl 68, ratchet 35 70, shaft 54, sprocket 53, chain 52, and gears 30. 40 If the pawl 68 is raised, this positive drive is temporarily interrupted until the pawl 69 engages the next tooth on the ratchet. Normally the pawl 68 remains in engagement with the ratchet but whenever there is an excessive over feed, the 45 same is moved out of engagement with the ratchet to introduce the aforesaid correction. In order to move the pawl 68 out of engagement with the ratchet, I provide a lever 73 pivoted at 74 to a bracket 75 mounted on the frame 20 and one end 50 of this lever 73 is provided with an extension 76 which is normally in inoperative position as illustrated by dotted lines in Fig. 8. In this position, the same cannot move the pawl out of engagement with the ratchet. However, when the 55 solenoid 43 is actuated to move the rod 44 upwardly to the position shown in Fig. 8, the rod 44 through the intermediacy of the link 17 rocks the lever 73 into the full line position shown in Fig. 8. This results in the 60 movement of the extension 76 into the path of movement of the cam 78 integral with the pawl 68. A similar cam 79 is integral with the pawl 69. The cam 78 riding over the extension 76 65 raises the pawl out of engagement with the ratchet and the disk 67 and ratchet 70 thereafter have a relative angular movement until the pawl 69 engages the operative face of the tooth on the ratchet. Means which will presently be described is provided for holding the extension 76 70 in operative position until the cam 79 on pawl 69 engages the extension 76 and is moved out of engagement with the ratchet in the same manner as the pawl 68. By this time, however, the cam 78 on pawl 68 has passed the extension 75

16 and is free to move into engagement with the ratchet. It is desired, however, to have the pawl 68 in position to engage the ratchet before the pawl 69 is moved out of engagement therewith 5 and for this purpose, I provide the rigid guide 80 which has a cam surface 81 for engaging the cams 78 and 79 on the pawls 68 and 69 respectively. When the cam 78 reaches the portion 82 of the cam 81, this portion of the cam forces the pawl positively toward the ratchet and insures 10 that the pawl will be in a position to engage a tooth on said ratchet before the pawl 69 is released. The releasing of the pawl 69 permits the ratchet to lag again until the pawl 68 engages a tooth. After the pawl 68 is again operative, the extension 76 can be, and is released. During the rotation of the disk 67, the pawls 68 and 69 are 15 positively held against movement away from the ratchet, except at their uppermost position illustrated in Fig. 2, and one pawl is always under the guide 80. This insures that there will always be a driving connection between the ratchet and disk. If the machine should be stopped suddenly 20 the ratchet cannot overrun because the pawls cannot, while beneath guide 80, move away from the ratchet a distance sufficient to permit the ratchet to advance. Similarly if and when the operator "backs off" the machine, the reversal 25 of the movement of the parts will not cause relative rotation between the pawls and ratchet for the same reason. The result is that the parts always are kept in proper adjustment.

The link 77 is provided with teeth 83 to form 30 a sort of rack bar. A pawl 84 pivoted on a shaft 35 85 is normally urged toward the link 77 by a spring 86. See Fig. 1. Therefore, if the link 77 is raised by the solenoid 43, the link is held against downward movement by the engagement 40 of the pawl 84 with the teeth 83 on the link until such time as the pawl 84 is released. In view of the fact that the contacts 62 and 41 are in engagement only for a short interval of time and the actuation of the bar 44 is therefore only for a very short period, it is necessary to provide such 45 a mechanism as has been described for holding the link 77 in raised position for a predetermined time sufficient to enable the extension 76 to operate the pawls 68 and 69 in the manner described. After the pawl 69 has been raised out of engagement 50 with the ratchet, the pawl 84 may be released to permit the link 77 to drop, thereby restoring the lever 73 to its inoperative position. The means for releasing the pawl 84 operates in timed relation with the drive to the shaft 47 and 55 comprises a lever 87 pivoted on the shaft 85 and having a pin 88 extending into a position in front of the pawl 84. See Fig. 1. The lower end of the lever 87 is normally urged against the pin 88 by the spring 87'. In order to move the lower end 60 of the lever to the right and thereby release the pawl 84, I provide a pin 89 which engages the lower end of the lever 87 at each rotation of the gear 56. Therefore at each revolution of the gears 56, the pawl 84 is released and the extension 76 restored to an inoperative position. Rollers 95 guide the link 77 and pin 96 engages pawl 84 and prevents the same from moving into engagement with the link 77 with too great a pressure. The solenoid might not raise the link if 65 too much pressure were exerted thereon by the pawl at the same time the pawl should be held firmly in operative position.

In order to shield the photo-electric cell 27 from light which may be projected thereon, other than 70 from the source of light 34, I provide a tubular

shield 90 secured to the end of an arm 91 pivoted at 92 to the guide 25 or to any fixed support. The center of gravity of the shield 90 is to the left of the pivot 92 and therefore the shield tends to rotate to the right against the web 28 and 5 casing 26. This not only holds the web firmly against the casing 26, but also forms a substantially light-tight housing for the beam of light for an appreciable distance away from the casing. A spring could be used to move the shield 10 against the web if desired, but the pendulous action of the shield 90 acts as a yielding means for pressing the shield against the web and is very simple to construct. Furthermore, it permits the shield to be moved to an inoperative position, very 15 readily in case it is desired to inspect the web when an adjustment of the web is desired. This means for shielding the web is important in view of the fact that if for instance at the time the beam is cut by one of the markings C, some other 20 source of light outside the machine such as the light of a match which the operator may be using, or of a light bulb may cause a sufficient intensity of light passing through the opening 28 to prevent the operation of the relay 36 by the 25 photo-electric cell 27. The shield 90, however, substantially prevents any light from entering the opening 28 except that light which comes from the source of light 34.

The operation of the device which has been 30 described is as follows: Before the machine is set in motion, the operator sets the web so that it occupies with respect to the positions A and B, a 35 position such as that shown in Fig. 5. The web is fed by means of the rolls 29 and the same is cut by the knives 32 to form the strips 33. If the light from the source 34 is passing freely through the web as it would in Fig. 5, the photo-electric cell receives a sufficient amount of light to prevent operation of the relay 36. If, however, the 40 over feed accumulates until the markings C¹ arrive at the position A as in Fig. 6, a part of the light is screened from the photo-electric cell 27, and this operates the relay 36. If at the instant 45 of presentation of the marking C¹, opposite the opening 28, the contacts 62 and 41 are closed, then the solenoid can be energized and the link 77 raised to the position shown in Figs. 1 and 8. The pawl 84 engages the teeth 83 and holds the link 77 upwardly a sufficient length of time to permit 50 the extension 76 to successively raise the pawls 68 and 69, and thereafter the lever 87 is rocked by the pin 89 to release the pawl 84, and this permits the link 77 to move downwardly by gravity and rock the extension 76 to an inoperative position. The successive movements of the extension 76 out of and into operative position introduces a 55 relative angular displacement between disk 67 and ratchet 70 as previously described, so that the feed for the rolls 29 lags and the markings C² drop back to a position such as illustrated in Fig. 7, it being understood that the position A not only indicates the position of the light source but also indicates the instant of closing of the contacts 41 and 62, for it is obvious that all of the 60 markings at one time or another are covering the opening 28 and cut off the supply of light to the photo-electric cell 27. It is only when the markings screen the light at the instant the contacts 62 and 41 are closed that operation of the correcting mechanism becomes operative.

During the feeding of the web, the shield 90 is yieldingly pressed into contact with the web due to its gravitational movement to the right about the pivot 92.

Obviously those skilled in the art to which this invention pertains may make various changes in the particular arrangement and construction of parts shown in the drawings without departing 5 from the spirit of this invention and therefore I do not wish to be limited except as hereinafter set forth in the appended claims.

Having thus fully described my invention, what I claim as new and desire to obtain by Letters 10 Patent is:

1. A web feeding mechanism for feeding webs having indicia thereon at predetermined points along said web comprising feeding means for feeding said web along a predetermined path, a 15 rotatable driven element connected to said feeding means, a rotatable driving element rotatable on an axis coincidental with the axis of rotation of said driven element and actuated continuously, a releasable connection between said driving and driven element for connecting the same in driving relation with each other comprising a plurality of pawls on one of said elements, a ratchet on the other of said elements, means for urging said pawls into engagement with said ratchet, said pawls being spaced from each other 20 a distance such that only one of said pawls is in engagement with the operative face of a tooth on said ratchet, means operable when the feed of said web varies more than a predetermined 25 amount from that desired for moving said pawl which is in engagement with the tooth on said ratchet out of engagement with said tooth to thereby permit relative movement between said elements until the other of said pawls comes into 30 engagement with a tooth on said ratchet and stops the relative rotation between said elements, whereby the total amount of actuation of said feeding means by said driven element is varied 35 from that which would occur if said first pawl was in engagement with said ratchet and remained operative.

2. A device as set forth in claim 5 which includes means for releasing said second pawl from its operative engagement with its tooth on said 45 ratchet and also includes means for moving said first pawl toward said ratchet to a position opposed to but not in engagement with the operative face of a tooth prior to the release of said second pawl, whereby one pawl is always in operative position to engage a tooth on said ratchet to establish a driving connection between said elements.

3. A web feeding mechanism for feeding webs having indicia thereon at predetermined points 55 along said web comprising feeding means for feeding a web along a predetermined path, a rotatable driven element connected to said feeding means for actuating the same, a rotatable driving element for driving said driven element, a pawl on one of said elements, a ratchet on the other of said elements, detecting means cooperating with the indicia on said web for detecting when said web is being fed a total amount which varies from the desired total amount, means for releasing said pawl from its operative engagement with a tooth on said ratchet and means for thereafter engaging said pawl with said ratchet after a predetermined relative movement between said elements, said releasing means being 65 operatively controlled by said detecting means.

4. A web feeding mechanism for feeding webs having indicia thereon at predetermined points along said web comprising feeding means for feeding a web along a predetermined path, a 70 rotatable driven element connected to said feed-

ing means, a rotatable driving element, a pair of pawls on one of said elements, a ratchet on the other of said elements engaged by said pawls, said pawls being spaced with respect to said ratchet in such a manner that only one of said pawls can engage the operative face of a tooth thereon to establish driving connection between said elements, the other of said pawls being in a position to engage the operative face of a tooth when said first pawl is released, mechanism for 10 positively preventing movement of said pawls away from the aforesaid operative position except at a predetermined position in their path of movement, means located adjacent said position for moving said pawls successively in the 15 order named away from said ratchet, said movement preventing mechanism including a part operable for moving said first pawl into a position to engage a tooth on said ratchet prior to release of said second pawl, and means cooperating with the indicia on said web for actuating said means for moving said pawls successively out of engagement with said ratchet operable upon a variation in the feed of said web beyond predetermined limits, whereby the relative movement between said elements resulting from the release of said pawls and reestablishing of the connection between said first pawl and said ratchet results in a relative rotation between said 20 elements to vary the drive to said feeding means. 25

5. A web feeding mechanism for feeding webs having indicia thereon comprising feeding means for feeding a web along a predetermined path, a pair of rotatable elements relatively movable with respect to each other, a pair of pawls on one 30 of said elements, a ratchet on the other of said elements in a position to be engaged by said pawls, yielding means for urging said pawls toward said ratchet, a fixed guide for engaging means on said pawls to hold them against movement away from said ratchet throughout all but a relatively small portion of their path of travel, means positioned adjacent said portion of said path of travel of said pawls movable when operated into a position to raise said pawls out of 35 engagement with said ratchet successively, the pawls being spaced about said ratchet more than a multiple of the distance between adjacent teeth, whereby only one pawl is operative at one time, said guide being operable for establishing 40 connection between the first of the pawls moved out of engagement with the ratchet before the other of the pawls is moved out of engagement with the ratchet, and means cooperating with the 45 indicia on said web for operating means which releases said pawls. 50

6. A web feeding mechanism for feeding webs having indicia thereon comprising feeding means for feeding a web along a predetermined path, a pair of rotatable elements, relatively movable 60 with respect to each other, a pair of pawls on one of said elements, a ratchet on the other of said elements in a position to be engaged by said pawls, yielding means for urging said pawls toward said ratchet, a fixed guide for engaging means on said pawls to hold them against movement away from said ratchet throughout all but a relatively small portion of their path of travel, means positioned adjacent said portion of said path of travel of said pawls movable when operated into a position to raise said pawls out of 65 engagement with said ratchet successively, the pawls being spaced about said ratchet more than a multiple of the distance between adjacent teeth, whereby only one pawl is operative at one 70

75 rotatable driven element connected to said feed-

time, said guide being operable for establishing connection between the first of the pawls moved out of engagement with the ratchet before the other of the pawls is moved out of engagement 5 with the ratchet, and means cooperating with the indicia on said web for operating the means which releases said pawls, said means which cooperates with the indicia on said web comprising an electric eye cooperating with said indicia 10 and operable when said indicia arrives at a given position at a time which varies from the time the same should arrive at said position more than a predetermined amount.

7. A device as set forth in claim 10 in which 15 the means for moving the means for releasing said pawls into operative position comprises a solenoid, a rack bar movable in one direction by said solenoid, a pawl cooperating with the teeth on said rack bar for preventing reverse movement of said rack bar after the same has been moved by said solenoid, and means operable to release said pawl to permit movement of said rack bar in a direction opposite to the movement imparted thereto by said solenoid, whereby 20 25 the means for releasing said pawls is moved to an inoperative position.

8. A device of the class described comprising a source of light for cooperating with indicia on a web being fed, a photo-electric cell, a casing for 30 said photo-electric cell having an opening adjacent said web, a shield mounted on the side of said web away from said casing, means engaging the shield and yieldingly pressing the shield against said web to hold said web against said 35 casing in proper relation to said opening and prevent a portion of the light from other sources than from said light beam from reaching said photo-electric cell, said shield being pivotally mounted at a point to one side of a vertical plane 40 through the center of gravity thereof in a direction toward said web, whereby the pendulous action of said shield moves the same against said web and presses the web against said casing.

9. A web feeding mechanism for feeding webs 45 having indicia thereon at predetermined points along said web comprising feeding means for feeding a web along a predetermined path, a drive to said feeding means including a pawl and ratchet, means for detecting when said indicia 50 arrives at a predetermined position in its path of movement at a time which varies from the time at which said indicia should arrive in said position more than a predetermined amount and for releasing said pawl to disconnect the drive to said feeding means, means for thereafter establishing 55 driving connection between said pawl and ratchet after said pawl and ratchet have moved relatively to each other and said pawl is in a position to engage a different tooth on said ratchet, whereby 60 to vary the feed to said web, the pawl being moved into engagement with said ratchet after the feed of said web is adjusted in the direction to more nearly approach the desired feed for the same and being held positively against movement 65 away from said ratchet beyond the ends of the teeth on said ratchet except at selected times, whereby even movement of said pawl relative to said ratchet in a direction opposite to the normal movement of said pawl toward said ratchet 70 will not enable the pawl to slip over a tooth and as a result upon the reestablishment of the normal movement of the parts, the same tooth on said ratchet will be engaged by said pawl.

10. A web feeding mechanism for feeding webs 75 having indicia thereon comprising feeding means

for feeding a web along a predetermined path, a pair of rotatable elements relatively movable with respect to each other, a pair of pawls on one of said elements, a ratchet on the other of said elements in a position to be engaged by said pawls, 5 yielding means for urging said pawls toward said ratchet, a fixed guide for engaging means on said pawls to hold them positively against movement beyond the ends of the teeth on said ratchet throughout all but a relatively small portion of 10 their path of travel, means positioned adjacent said portion of said path of travel of said pawls movable when operated into a position to raise said pawls out of engagement with said ratchet successively, the pawls being spaced about said 15 ratchet more than a multiple of the distance between adjacent teeth, whereby only one pawl is operative at one time, said guide having provisions for establishing connection between the first of the pawls moved out of engagement with the 20 ratchet before the other of the pawls is moved out of engagement with the ratchet, and means cooperating with the indicia on said web for operating the means which releases said pawls, one of said pawls being acted on by said guide at all 25 times.

11. In a web feeding device, means for feeding a web, said web having indicia thereon, driving means for said feeding means, connections between the driving means and feeding means, 30 means for performing an operation on the web at spaced intervals thereon, means responsive to the relative position of the indicia on the web and the last named means, means acting in timed relationship with said last named means, and 35 means operable when the last two means operate simultaneously for releasing the connections between the feeding means and the driving means, and means for re-establishing said connections after a predetermined relative movement between the web feeding means and the driving means.

12. In a web feeding device, means for feeding a web, said web having indicia thereon, driving connections for said feeding means, means for 45 performing an operation on the web with spaced intervals thereon, photo-electric means responsive to the relative position of the indicia on the web and the last named, a timer element making intermittent electrical contact, means operable 50 only when the indicia is at a predetermined position and the timer is in a position to make electrical contact for releasing the driving connections at a predetermined position of the feeding means, and means for re-establishing the 55 connections after a predetermined movement of the feeding means.

13. In a web feeding mechanism, the combination with means for feeding a web along a predetermined path including a pair of relatively 60 movable elements, of means for releasably establishing a positive driving connection therebetween, means for releasing said last mentioned means to permit relative shifting of said relatively movable elements, sensing means, means 65 operable in timed relationship with the movement of the web, means controlled jointly by said sensing means and by said last named means for operating said releasing means, means for re-establishing said positive driving connection 70 after said elements have moved relatively to each other a predetermined amount, and means for positively preventing the driving connection from being released except when desired and irrespective of the direction in which said elements 75

have a tendency to move relative to each other.

14. In a device of the class described having means for feeding a web and means for sensing indicia on the web including a light source and a photo-electric cell, the combination of a shield arranged in the path of travel of the light and positioned to screen the light rays reaching the cell, said shield being pivotally mounted for movement from inoperative to operative positions about an axis eccentrically disposed with respect to the center of mass of the shield whereby when in operative position said shield will be yieldably urged by gravity into engagement with the web to tension the web and maintain it in proper position.

15. In a device of the class described having means for feeding a web and means for sensing indicia on the web including a light source and a photo-electric cell, the combination of a shield arranged in the path of travel of the light and

positioned to screen the light rays reaching the cell, said shield being eccentrically pivoted relative to its center of mass whereby to be yieldably urged by gravity against the web to tension the web and maintain it in proper position. 5

16. In a web sensing device, a light source, a photo-electric cell, a shield arranged between the light source and the cell in the path of the light rays, and means for feeding a web between said shield and said cell, said shield being mounted for movement from inoperative to operative positions about an axis eccentrically disposed with respect to the center of mass of the shield whereby when in operative position said shield will be yieldably urged by gravity against the web whereby to clamp the web between the shield and the cell and maintain it in proper operative position. 10 15
